CYLINDER LINER FOR OPPOSED PISTON ENGINES

Hans Steiner, Winterthur, Switzerland, assignor to Sulzer Freres, Societe Anonyme, Winterthur, Switzerland

Application August 9, 1945, Serial No. 609,859
In Switzerland September 26, 1944

6 Claims. (Cl. 123—173)

1

This invention relates to a cylinder liner for internal combustion engines with opposed pistons, the middle part of the liner being cooled by a cooling-medium introduced through passages, and consists in that the inner surface of the cylinder liner deviates from the cylindrical shape in the middle part not passed over by the piston rings. In this way greater freedom is obtained with respect to the arranging of the bores for the cooling-medium and a better cooling of the inner surfaces of the cylinder, resulting in lower cylinder-wall temperatures, lower lubricating oil consumption and less thermal stresses.

Three embodiments of the invention are shown diagrammatically in the accompanying drawings, in which:

Fig. 1 is a longitudinal section through the cylinder liner of an opposed-piston internal combustion engine;

Fig. 2 illustrates, on a larger scale, the middle part of the liner shown in Fig. 1; and

Figs. 3 and 4 illustrate modified shapes of the middle part of the cylinder liner.

In Fig. 1 the two pistons 2 and 3 in the cylinder liner 1 are shown at the inner dead centre. The scavenging, or charging and supercharging air, enters the cylinder through the scavenging ports 4. The exhaust gases leave the cylinder through the exhaust ports 5. In the strengthened middle part 6, the cooling-medium is led through passages 29 which run obliquely to the cylinder axis 20, the axes of the passages 29 belonging to the generating lines of a hyperboloid of revolution of one sheet whose axis of revolution is the cylinder axis 20 and whose fundamental circle lies in the middle plane 21 through the cylinder. Consequently in the plane 21 the distance of the passages 29 from the cylinder axis 20 is the smallest.

In contrast to known constructions, the inner diameter of the cylinder liner 1 at its central portion 22, not swept by the piston rings 30, deviates from the cylindrical shape in that it diminishes as the middle sectional plane 21 is approached in such a way that its inner surface conforms to the run of the cooling passages 29 to provide at least a constant wall thickness in that inner surface and those cooling passages. The inner surface of the liner 1 thus adopts in the zone 22 at least approximately the form of a hyperboloid revolution with the cylinder axis 20 as axis of revolution. Therefore, although the cooling passages 29 come nearest to the cylinder axis 20 in the middle sectional plane 21, their distance from the inner surface of the liner remains small in the zone in which the piston rings 30 lie at inner

5 dead center. Because of this special form of inner surface of the liner 1, it is possible, as shown in Fig. 1, to make a satisfactory cylinder liner with only one series of bores 29 made from one side of the strengthened middle part 6 straight through to the other, and, nevertheless, to have a sufficient distance separating them from the inner surface of the cylinder liner 1 in the neighborhood of its middle sectional plane 21 to provide the desired distribution of temperature in the wall. Naturally the crowns of the pistons must be so shaped that they do not knock against the wall of the cylinder liner 1 in the reduced zone 22.

15 Fig. 2 shows the strengthened middle part 6 of the cylinder liner 1 of Fig. 1 on a larger scale. The sectional plane on which this drawing is taken cuts the ellipses 7, 8, 9, 10 and 11 in intersecting these cooling passages 29. The dash-dotted line a—a is the line of section of a surface of rotation which contains the center lines of all the cooling passage 29. The internal diameter of the cylinder liner diminishes from A and B toward the middle sectional plane 21 of the cylinder, as explained in the above, in connection with Fig. 1. Correspondingly, the diameter of the piston crown 27 and 28 is smaller than the diameter of the piston barrels. Thus, the wall thickness between the cooling passages and inner surface of the liner may even increase toward the middle sectional plane of the cylinder, thus causing a higher wall temperature in zone 22 not swept by the piston rings without any attendant danger. On the other hand, if the engine is subjected to high thermal stresses, it may be advisable to allow the wall thickness between the gas-heated surface and the passages to decrease towards the middle of the cylinder, in order that this zone, where heat exchange is greatest, may be relieved from heat stresses as much as possible. 20 By a suitable choice of the run of the diameter between A and B, and further by suitable arranging of the cooling-passages, the course taken by the cylinder wall temperature can be effectively 25 influenced.

In the embodiment shown in Fig. 3 the cooling-medium passages also run obliquely to the cylinder axis. The sectional plane on which this figure is taken produces the ellipses 12, 13, 14, 15, 16, 17, 18 and 19 in intersecting these cooling 30 passages. The middle part 6, however, is in this construction bored from both sides 6', 6'' in such a way that the axes of all passages on each side of the middle plane 21 lie each on a hyperboloid of revolution of one sheet, so that the distance of

the bores from the cylinder axis is smallest outside the cylinder middle plane 21, and increases again towards the middle plane. Each part passage bored from one side of the strengthened middle part 6 intersects a similar part passage bored from the other side in the cylinder middle plane 21 thus together forming by couples 12-13, 14-15, 16-17 and 18-19, for example, a continuous passage for the cooling-medium.

Through this arrangement very effective cooling is obtained of the zone in which the piston rings 23 are at their inner dead centre. Also here the run of the cylinder inner wall 24 deviates from the straight in the middle zone and follows approximately the run of the cooling-bores, whereby the heat stresses in the cylinder wall are diminished.

In the embodiment shown in Fig. 4 the strengthened middle part 6 is also bored from the two sides 6' and 6'', but here the axes of the bores each lie on a circular cone. Related bores, such as 25 and 26 intersect in the middle plane of the cylinder. By reducing the internal diameter of the cylinder in the middle zone the effect obtained is similar to that described in the case of Fig. 2.

Through the invention better cooling is obtained of the running surfaces or of the pistons of internal combustion engines.

I claim:

1. A cylinder liner for opposed piston internal combustion engines having a strengthened middle part surrounding the combustion chamber, a plurality of passages in said middle part oblique to the axis of the cylinder for the circulation of a cooling medium, the inner surface of said strengthened middle part of the liner not swept by the piston rings deviating from the cylindrical shape.

2. A cylinder liner as claimed in claim 1, the wall thickness of which between the cooling passages and the inner surface deviating from the cylindrical shape is approximately constant.

3. A cylinder liner as claimed in claim 1, the wall thickness of which between the cooling passages and the inner surface deviating from the cylindrical shape is, at least in some places,

greater than in the zones in which the piston rings are situated when the pistons are in their inner dead center.

4. A cylinder liner as claimed in claim 1, the diameter of the inner surface of which in the middle part not swept by the piston rings is smaller than the diameter of the inner surface of the remaining part of the liner.

5. A cylinder liner for opposed piston internal combustion engines having a strengthened middle part surrounding the combustion chamber, a plurality of passages in said middle part oblique to the axis of the cylinder for the circulation of a cooling medium, said passages being so arranged that their axes belong to the generating lines of a single-sided hyperboloid of revolution and that their distance from the cylinder axis decreases to a minimum in substantially the middle sectional plane of the cylinder liner, the inner surface of said middle part being shaped as a single-sided hyperboloid of revolution so that the wall thickness between the cooling passages and the inner surface of the liner is at least approximately constant.

6. A cylinder liner for opposed piston internal combustion engines having a strengthened middle part surrounding the combustion chamber, a plurality of angular passages in said middle part for the circulation of a cooling medium, each of said passages having a vertex at substantially the middle sectional plane of the cylinder, the wall thickness between said passages and the inner surface of the liner in the middle part not swept by the piston rings being at least approximately constant.

HANS STEINER.
